UNITED STATES PATENT OFFICE

164,003

MUSIC BOX

Lloyd G. Kelley, Hanover, Mass.

Application October 20, 1950, Serial No. 12,636

Term of patent 14 years

(Cl. D56—1)

To all whom it may concern:

Be it known that I, Lloyd G. Kelley, a citizen of the United States and residing at Hanover, county of Plymouth, and Commonwealth of Massachusetts, have invented a new, original, and ornamental Design for a Music Box, of which the following is a specification, reference being had to the accompanying drawings, forming a part thereof.

Fig. 1 is a front elevational view of a music box showing my new design;

Fig. 2 is a rear elevational view; and

Fig. 3 is a top plan view.

The dominant features of my design reside in that portion shown in full lines in the drawing.

I claim:

The ornamental design for a music box, as shown and described.

LLOYD G. KELLEY.
